COMBINED STRING RETAINER AND CUTTER STRUCTURE

Frederick P. Upton, New Rochelle, N. Y.

Application October 7, 1948, Serial No. 53,363

8 Claims. (Cl. 30—127)

1

This invention relates to a combination string or cord retainer or holder and a cutter structure.

It happens that in almost every family that string or cord is required for tying up packages or bundles and many times the string or ball of twine or cord gets misplaced and causes a lot of trouble and annoyance in looking for it.

It is therefore the object of my invention to provide a receptacle or retainer for carrying a ball of string, twine or cord which may be mounted in a most convenient place, ordinarily such a place is in the kitchen. Another object of my invention is to provide a structure in which there is associated a cutting means for easily and quickly cutting off the string or cord as it is withdrawn from the receptacle or retainer. A further object is to provide a lock associated with the cutter that will hold the string in a visible position where it may be readily grasped by an operator and pulled out of the retainer into proper relation with the cutter so the cord, string or twine can be quickly cut off and the supply end held in visible position for use on another occasion. Another object of my invention is to provide a retainer for a ball of string or cord of a size that will take balls that are rolled up concentrically or balls that are rolled up on a bias. This latter type of ball takes up more room than a round ball, so I have provided a container that will take either type of ball so that the same may have a rotary motion or end over motion or a combination of both, as the string or cord is withdrawn from the container. Another object of my invention is to provide a retainer which is readily accessible for inserting the ball of cord thereto, at the same time to provide a container that can be easily and quickly mounted in operative position.

In the drawing,

Figure 1 is a side elevation of the complete structure on a reduced scale.

Figure 2 is an end view of Figure 1 looking at Figure 1 from the bottom towards the top, the top end mounting means being shown in dotted lines.

Figure 3 is a view of the cutter with the parts in one operating position and a string or cord being in position to be cut off.

Figure 4 is a view of the left end of Figure 3, with the cutter shown mounted on the end of the container.

Figure 5 is a view of Figure 3 looking from right to left but with the cutter parts in a position just after the cord or string has been severed and with the string about to be forced into the

2

holding position, the broken lines indicating the position of the movable member of the cutter in its position before starting the cutting operation about as shown in Figure 3.

5 In the different views wherein like numbers refer to corresponding parts,

1 is a receptacle or retainer made of any suitable material preferably plastic so it may be molded in different colors or even a combination of colors in the same device. One end of the retainer has an outwardly curved rim 2 having therein notches 3 to receive lugs 4 on a mounting plate 5 whereby the plate 5 may be locked in position by the lugs 4 which may be considered a bayonet type of locking means on turning the plate 5 to the position shown. Preferably one of the lugs 6 is wider than the others and likewise its corresponding notch 3'. Adjacent to notch 3' is a stop 7 which may be a screw set into the flange 2 or a projection molded thereon. This is to prevent the lug 6 from being moved in a right hand direction looking at Figure 2, but allowing it to be moved left handed until it reaches a stop 8 similar to stop 7. This is so that the mounting hole 9 and its co-operative slot 10 in the mounting plate 5 is in alignment with the hole 11 in the opposite end of the retainer so that when the device is mounted through the medium of a screw or nail, by passing its head through the hole 9 and its shank into the slot 10, the string 12 coming out of the hole 11 will be directly in transverse alignment with the cutter 13 which is placed, as shown in Figure 2 so as to be transversely located across a diameter from the hole 11, for a purpose which will be readily understood from what follows:

The cutter structure may be considered as a combined gripping and cutting means made up of two channel shaped members 14 and 15. 40 Channel 15 has one of its flanges 16 located immediately adjacent the flange 17 on the member 14. Also the member 15 has its other flange 18 located adjacent to, but outside of the flange 19 of the member 14. The two members 14 and 15 are pivoted together at one end by a stud or pin 20. Carried on the stud or pin 20 is a helical spring 21 which is formed and located so as to hold the co-operating flanges in contact with each other, but should the string 12 be of a size larger than the ordinary, then the member 15, when moved down in a cutting operation, will be shifted laterally in the direction of the arrow so as to allow the cutting edges 22 and 23 to better perform the cutting operation and also to provide a little more room at the point 24 where

the cord or string is held after the cutting operation by the two flanges 16 and 17. It is to be noted that the member 14 is fastened to the end 25 of the box by the screws 26 also that the flange 16 is somewhat narrower than the flange 18 so as to allow the cutting flanges and cutting edges 22 and 23 to cut the string 12 just before it is gripped by the flanges 16 and 17. This construction is preferable since it allows the cutting edges 22 and 23 to be in the best cutting position or in close co-operation before any lateral pressure is applied to flange 16 as it pushes the cord down into locking position between the flanges 16 and 17. It will be noted that the pin 20 is so constructed as to allow a small lateral movement of member 15. Also it is to be noted that the flange 16 is turned slightly inward especially at its free end so as to form its gripping and holding action without a tendency to cut the string or cord coming from the ball B shown in dotted lines in Figures 1 and 2. The movable flange member 15 has its web 27 extended for the operator to take hold of in moving the member 15 during the cutting operation. By having the cutter composed of the members 14 and 15 arranged transversely to the hole 11, the string will find a position across the fixed member 14 as illustrated in Figure 3 so to enable the operator to take hold of the lip 27 and open the cutting member 15 to position as shown in Figure 3 and then after pulling out a length of string desired, the member 15 is moved downward to the position shown in Figure 5 where the string is cut.

Having thus described my invention what I claim is.

1. A structure including a receptacle for carrying string and having an exit opening for the string, means for supporting the receptacle, a combined gripping and cutting means mounted on the receptacle so a string coming from the receptacle will pass across said gripping and cutting means, said gripping and cutting means comprising a channel shaped member fastened to an outer wall of the receptacle and another channel shaped member pivotally mounted at one end to one end of the first mentioned channel member, each channel shaped member having a web with spaced flanges extending therefrom, said pivoted channel member being transversely positioned on its pivot so one of its flanges will pass just inside of the fixed channel flange nearest to said exit opening, while the other flange of the pivoted channel member will pass just outside the other flange of the fixed channel, these last two mentioned flanges having cutting edges to cut a string pulled from the receptacle exit opening across the two sets of flanges, the first mentioned set of flanges acting to hold the string in position after the string has been cut by said cutting edges so it may be quickly engaged by an operator and drawn across all the flanges on raising the pivoted member.

2. A structure including a receptacle for carrying string and having an exit opening for the string, means for supporting the receptacle, a combined gripping and cutting means mounted on the bottom of the receptacle in transverse alignment with the string opening so the string end by itself will normally intercept the gripping and cutting means, said means comprising a pair of channel shaped members having co-operative flanges transversely arranged and operatively held together at one end by a pivot pin so the free edges of the flanges of one of said members are closely adjacent the flanges of the other, one

member being non-movably fixed to the string receptacle while the other is pivotally movable on the fixed member, the pair of co-operative flanges farthest from the string exit opening having 5 scissors like cutting edges to cut the string while the pair of co-operative flanges nearest the string opening has dull edges so as to grip and hold the string after the cutting edges have cut the string on operating the pivotally movable channel member whereby the string will be available for another cutting operation.

3. A combined string receptacle and cutter structure having gripping and cutting means as defined in claim 2 further characterized in that the flange, on the fixed channel member which is nearest the source of string exit opening is not as wide as its cutting flange for the purpose described.

4. A combined string receptacle and cutter structure having gripping and cutting means as defined in claim 2 further characterized in that spring means are located within the confines of the channels for laterally shifting the movable channel member on the pivot pin when necessary, depending on the diameter of the string being cut and to better cut the string or cord that is drawn into cutting position on the cutter.

5. A combined string receptacle and cutter structure having gripping and cutting means as defined in claim 2 further characterized in that a helical spring is positioned on the pin between the dull edge of the movable channel member and the cutting flange of the fixed channel member, so the movable channel member may shift laterally away from the fixed channel member to automatically take up at least a better locking position for a string or cord of larger diameter than those that are small enough in diameter so no shifting of the cutting channel member takes place.

6. A combined string receptacle and cutter structure having gripping and cutting means as defined in claim 2 further characterized in that the movable channel member has a pair of flanges connected by a web and has its web extending outwardly beyond the free end of its flanges to form a handle for operating the said channel.

7. A structure including a cylindrically shaped casing for carrying string or cord with means at one end for receiving means for supporting it, said end being removable for introducing the string or cord, the opposite end having a hole therein near the outer edge of said end, combined gripping and cutting means carried by this last mentioned end and positioned transversely across a diameter of the casing passing through the center of said hole, so a string or cord coming out of the hole may be hung across said gripping and cutting means, said means being composed of two channel shaped members having co-operative flanges, one member being non-movably fixed while the other member is pivoted at one end to the fixed member so the cooperative flanges of the channel members are in lateral engagement, the set of flanges farthest from said hole having co-operative cutting edges to cut the string or cord while the set of co-operative flanges nearest to the hole has dull edges to grip and hold the string or cord after it is severed by said cutting flanges.

8. A structure including a casing having means for placing string or cord therewithin and also having co-operative means for mounting it for use, the casing having exit means for the string
